CLAIM

The ornamental design for a protector and conditioner for an electrical plug, as shown and described.

DESCRIPTION

FIG. 1 is a top perspective view of the protector and conditioner for an electrical plug of the instant invention;

FIG. 2 is a side view thereof;

FIG. 3 is a top view thereof;

FIG. 4 is a bottom view thereof; and,

FIG. 5 is a perspective view thereof, with the environment shown in broken lines.

The broken lines shown in the drawings are included for the purpose of illustrating environmental structure and form no part of the claimed design.
